UNITED STATES PATENT OFFICE

157,596

SPOON OR SIMILAR ARTICLE

George Honnet, Wilmington, N. C.

Application May 24, 1949, Serial No. 2,851

Term of patent 14 years

(Cl. D54—12)

To all whom it may concern:

Be it known that I, George Honnet, a citizen of the United States of America, residing at Wilmington, in the county of New Hanover and State of North Carolina, have invented a new, original, and ornamental Design for Spoon or Similar Article, of which the following is a specification, reference being had to the accompanying drawing, forming a part thereof, wherein:

Fig. 1 is a front elevation of a spoon, showing my new design;

Fig. 2, a rear elevation thereof;

Fig. 3, a fragmentary front elevation of the upper portion of the spoon handle on a somewhat enlarged scale; and,

Fig. 4, a fragmentary rear elevation of the

upper portion of the spoon handle also on an enlarged scale.

I claim:

The ornamental design for a spoon or similar article, as shown and described.

GEORGE HONNET.
